DESIGN FOR A BUCKLE

Francis X. Lipari, New York, N. Y.

Application October 5, 1942, Serial No. 108,438

Term of patent 7 years

To all whom it may concern:

Be it known that I, Francis X. Lipari, a citizen of the United States of America, residing in New York city, county of New York, and State of New York, have invented a new, original, and ornamental Design for a Buckle, of which the following is a specification, reference being had to the accompanying drawing, forming part thereof.

Fig. 1 is a plan view of a buckle showing my new design.

Fig. 2 is an edge view thereof.

I claim:

The ornamental design for a buckle, substantially as shown.

FRANCIS X. LIPARI.
